Leo F. Kengla INVENTOR

Joseph O'Brien BY ATTORNEY

UNITED STATES PATENT OFFICE.

LEO F. KENGLA, OF WESTCHESTER, NEW YORK.

DESIGN FOR A BUTTON, BADGE, EMBLEM, OR ARTICLE OF SIMILAR CHARACTER.

54,753.

Specification for Design.

Patented Mar. 23, 1920.

Application filed May 24, 1919. Serial No. 299,677. Term of patent 3½ years.

To all whom it may concern:

Be it known that I, LEO F. KENGLA, a citizen of the United States, residing at Westchester, Bronx county, and State of New York, have invented a new, original, and ornamental Design for a Button, Badge, Emblem, or Article of Similar Character, of which the following is a specification, reference being had to the accompanying drawing, forming part thereof.

The drawing herewith presented represents a plan view of a button, badge, emblem, or article of similar character, illustrating my design.

I claim:

The ornamental design for a button, badge, emblem, or article of similar character, as shown.

LEO F. KENGLA.
